UNITED STATES PATENT OFFICE.

HENRY W. LEONARD, OF SYRACUSE, AND JOHN STEVENS, OF PORT BYRON,
ASSIGNORS TO THE SYRACUSE PAPER WARE COMPANY, OF SYRACUSE,
NEW YORK.

CALENDERING-MACHINE FOR PAPER-PULP PAILS, &c.

SPECIFICATION forming part of Letters Patent No. 316,984, dated May 5, 1885.

Application filed July 21, 1884. (No model.)

To all whom it may concern:

Be it known that we, HENRY W. LEONARD and JOHN STEVENS, residing, respectively, at Syracuse, in the county of Onondaga and State 5 of New York, and Port Byron, in the county of Cayuga and State of New York, have invented new and useful Improvements in Calendering-Machines, of which the following is a specification.

10 This invention relates to an improvement in that class of calendering-machines for paper-pulp pails, &c., which consist of two tapering rollers, one mounted in stationary and the other in movable bearings, and which 15 are employed in calendering pails and similar tapering vessels made of paper or paper-pulp.

The object of our invention is to produce a machine of this kind which shall be strong and effective, and which can be easily and conveniently operated by the attendant; and our 20 invention consists of the improvements which will be hereinafter fully set forth, and pointed out in the claims.

In the accompanying drawings, consisting of 25 two sheets, Figure 1 is a side elevation, and Fig. 2 a front elevation, of our improved machine. Fig. 3 is a longitudinal section, and Fig. 4 a cross-section, of the upper part of the machine. Fig. 5 is a sectional top plan view of the 30 machine. Fig. 6 is a fragmentary cross-section of the lower cross-head on an enlarged scale.

Like letters of reference refer to like parts in the several figures.

A represents the stationary supporting-frame provided at its top with two curved parallel angle-bars, *a a*, on which is supported the upper adjustable frame, *A'*.

B represents the driving-roller which receives the pail or other vessel to be calendered, 40 and which is secured to the upper end of a vertical shaft, *b*. The latter is journaled in bearings *b' b'*, secured to the main frame *A*, and is driven by gear-wheels *b''*, or other suitable means.

45 C represents the adjustable roller, which is made movable toward and from the roller B, and which is pressed against the pail or other vessel placed on the roller B with sufficient force to calender said vessel. The roller C is

mounted loosely on a shaft, *c*, which is held at 50 its upper end in a cross-head, *D*, and at its lower end in a cross-head, *E*. The rollers B and C taper upwardly in accordance with the tapering form of the pails to be calendered. The shaft *c* stands at an angle to the shaft *b*, and 55 the supports *a* are curved in the arc of a circle concentric with the point in which the axes of the shafts *b* and *c* intersect each other, so that in adjusting the frame *A'* on the frame A the shafts *b* and *c* will remain radial to the 60 same point of intersection.

The frame *A'* consists of two side pieces, which are provided at their upper ends with bearings *d*, in which the upper cross-head, *D*, is journaled. The bearings *d* are made adjustable in these side pieces by set-screws *d'*. The lower sides of the base-pieces *e* of the upper frame, *A'*, are curved concentric with the supporting-pieces *a*, and connected by transverse bars *e'*, which rest on the curved supporting-pieces *a*. The latter are provided with longitudinal slots *e''*, through which pass the fastening-screws *e'''*, by which the frame *A'* is adjustably secured to the frame A. The base-pieces *e* are provided on their inner and upper 75 sides with angular recesses *f*, curved concentric with the axis of the upper cross-head, *D*. The lower cross head, *E*, is guided in the recesses *f* by rollers *f'*, attached to the cross-head and bearing against the outer sides of these recesses, while the ends of the cross-head rest upon the lower sides of said recesses, as clearly shown in Figs. 4 and 6. In moving toward and from the roller B the roller C swings, with the upper cross-head, *D*, on the journals of the latter and with the lower cross-head, *E*, in the 80 curved guides *f*.

G G represent toggle-levers secured to a horizontal shaft, *g*, which is journaled in bearings *g'*, secured to the rear portion of the lower 85 frame, *A*.

G' G' represent toggle-links connecting the levers G with the lower cross-head, *E*.

H represents a hand-lever secured to the shaft *g* and extending forwardly on one side of the rollers B and C, and terminating in convenient reach of the operator. By depressing the lever H the roller C is swung toward

the roller B², and by a reverse movement of the lever the roller C is removed from the roller B. 5 *h* represents a projection formed on the inner side of the lever H and bearing upon one of the toggle-levers G, thereby assisting in depressing the toggle-levers and preventing excessive strain on the shaft g.

i represents a pipe through which steam is supplied to the interior of the hollow roller C 10 by a bore or channel, *i'*, formed in the upper portion of the shaft c.

j is a pipe through which the waste steam is discharged from the roller C by means of a bore or channel, *j'*, formed in the lower portion 15 of the shaft c.

k represents a perforated pipe arranged along the rollers B and C, near their line of contact, for the purpose of delivering fine jets of moist steam upon the pail or other vessel 20 placed on the roller B. The pipe *k* is secured to the frame A', and receives its supply of steam from the discharge-pipe *j* by a flexible pipe, *k'*.

m represents a flexible pipe through which 25 the water of condensation and waste steam are discharged from the roller C.

The movement of the cross-head D on its journals is comparatively small, and it is therefore not necessary to make the upper 30 pipe, *i*, flexible if a long supply-pipe is used.

N represents a stuffing-box or packing applied to the upper end of the roller C to form a steam-tight joint with the shaft c. By heating the movable roller C the heat is applied 35 to the outer surface of the pail or other vessel placed on the roller B, whereby the calendering operation is rendered more effectual and a smoother finish is obtained.

The pail to be calendered is slipped on the 40 roller B, and the roller C is then pressed against the outer side of the pail by depressing the hand-lever H with sufficient force and for a sufficient length of time to produce the desired finish. The roller C is then withdrawn 45 by raising the lever H, and the calendered pail is removed from the roller B.

We claim as our invention—

1. In a machine for calendering paper pails, the combination, with a tapering roller mounted in stationary bearings and adapted to receive the pail to be calendered, of a hollow tapering roller made movable toward and from the stationary roller, and pipes whereby a heating agent is conducted through the 55 movable roller, substantially as set forth.

2. The combination, with a stationary tapering roller, of a movable tapering roller mounted on a shaft, a journaled cross-head in which one end of the shaft is supported, and a cross-head and curved guides, whereby the opposite end of the shaft is guided, substantially as set forth. 60

3. The combination, with the stationary roller B and the movable roller C, attached to a journaled cross-head, of toggle-bars and a lever, whereby the movable roller is swung toward and from the stationary roller, substantially as set forth. 65

4. The combination, with the tapering stationary roller B and the main frame A, in which said roller is journaled, and which is provided with curved supports *a*, of the movable tapering roller C and the supporting-frame A', adjustably secured to the curved supports *a*, substantially as set forth. 70

5. The combination, with the stationary roller B and movable roller C, of the toggle-lever G, link G', and hand-lever H, provided with a projection, *h*, bearing upon the lever G, substantially as set forth. 75

6. The combination, with the main frame A and adjustable frame A', of the stationary roller B, journaled in the frame A, movable roller C, mounted on the shaft c, cross-head D, journaled in the frame A', cross-head E, supporting the lower end of the shaft c, toggle-bars G G', and hand-lever H, substantially as set forth. 80

7. The combination, with the movable roller C, shaft c, and supporting-frame A', provided with curved guides *f*, of the cross-head E, provided with rollers *f'*, substantially as set forth. 85

8. The combination, with the stationary roller B, of the hollow movable roller C, steam supply and exit pipes *i j*, communicating with the hollow movable roller C, and a perforated steam-pipe, *k*, arranged to deliver jets upon the rollers near their line of contact, substantially as set forth. 90

Witness our hands this 7th day of May, 100
1884.

HENRY W. LEONARD.
JOHN STEVENS.
